[57] CLAIM

The ornamental design for a male erection sustainer, as shown and described.

DESCRIPTION

FIG. 1 is a perspective view of the male erection sustainer design of the present invention;
FIG. 2 is a front elevational view thereof, the rear elevational view being identical;
FIG. 3 is a side elevational view thereof; and,
FIG. 4 is a bottom plan view thereof, the top view being identical.

FIG. 1

FIG. 4

FIG. 3

FIG. 2
